UNITED STATES PATENT OFFICE

JOSEPH BECKER, OF PITTSBURGH, PENNSYLVANIA, ASSIGNOR TO THE KOPPERS COMPANY, OF PITTSBURGH, PENNSYLVANIA, A CORPORATION OF PENNSYLVANIA

COKING RETORT OVEN

Application filed May 16, 1921. Serial No. 470,198.

This invention comprehends improvements of especial utility in the coking retort oven art. The invention has for objects to provide the well-known Koppers cross-wise reversal principle in a cross-regenerative coking retort oven having horizontal flame flues in the heating walls, the application of the aforesaid reversal principle being preferably combined with reversal of combustion in the horizontal heating flues. The invention further provides for the optional utilization of the gas oven principle, in such a cross-regenerative oven, whereby the heat for coking the charges of coal in the retorts or coking chambers may be developed from the combustion of an extraneously derived special generator gas, such as producer gas, with conservation of the entire product of the relatively richer coke oven gas derived from the coal carbonization process carried on in the retort chambers.

In addition to the general objects recited above, the invention has for further objects such other improvements or advantages in construction and operation as may be found to obtain in the structures and devices hereinafter described or claimed.

In the accompanying drawings, forming a part of this specification and showing, for purposes of exemplification, preferred forms and manners in which the invention may be embodied and practiced, but without limiting the claimed invention specifically to such illustrative instance or instances:

Figure 1 is a crosswise vertical sectional elevation through a coke oven battery embodying features above specified and equipped with the improvements of the present invention, the view being taken longitudinally through a heating wall and a regenerator, in planes indicated by the line A—A of Fig. 2;

Fig. 2 is a composite vertical sectional elevation taken longitudinally of the coke oven battery, in planes indicated by the lines B—B, C—C, and D—D of Fig. 1; and

Fig. 3 is a similar composite vertical sectional elevation, but illustrating a modified form of construction of the regenerator system.

The same characters of reference designate the same parts in each of the several views of the drawings.

In the embodiment illustrated in the drawings, the invention is incorporated in a combination coke oven battery, i. e.,—a battery having provision for being operated either with an extraneously derived special generator gas, such as producer gas, or with the coke oven gas derived from the distillation of the coal in the coking chambers or retorts of the battery. For convenience, the present description will be confined to the present illustrated embodiment of the invention in such a combination coke oven battery; the novel features and improvements of the invention are capable of other applications, such, for example, as in ordinary so-called "gas ovens" employing producer gas as the fuel, or in ordinary so-called "coke ovens" employing coke oven gas as the fuel; hence, the scope of the invention is not confined to the specific use and specific embodiment herein described as an illustrative example.

Referring to the drawings, there are illustrated views of a coke oven battery or plant of the by-product type, having features above specified; said oven battery embodies in its construction a plurality of crosswise elongated heating walls 11, 11, and a plurality of intermediate crosswise elongated vertical coking chambers 12, 12. The heating walls 11 form the side walls of the respective coking chambers 12, shown more particularly in Fig. 2, and together with the coking chambers are supported by the heavy supporting walls 13, 13, which extend crosswise of the battery and are located, as shown in Fig. 2, below the coking chambers and heating walls. The supporting walls 13 collectively form the main support for the entire superstructure of the oven battery and are themselves supported upon a flat mat or platform which constitutes the sub-foundation on which the entire battery rests.

The coal to be coked is charged into the several coking chambers or ovens through charging holes 14 located in the top 15 of the oven battery and positioned, as shown in Fig. 2, directly above the ovens or chambers 12.

These charging holes 14 are equipped with the usual removable covers, which are removed during charging of the individual ovens or coking chambers and are placed in position to close the tops of such coking chambers during the entire coking or distilling operation. The gases of distillation pass from the tops of the several coking chambers 12 through gas outlets indicated by dotted lines at 16 in Fig. 1, and thence through ascension pipes (not shown) into the usual gas collecting main, which carries the distillation products to the by-product recovery apparatus.

15 Heat for coking the charges of coal in the several ovens or chambers 12 is derived from the heating walls 11, which, as above mentioned, extend cross-wise of the battery at the sides of the coking chambers. As shown, each 20 heating wall 11 is constituted of a plurality of individual horizontal flame or combustion flues 17, which extend parallel with the longitudinal axis of the heating wall. All of the flame flues of the heating wall, in accordance 25 with the present embodiment of the invention, operate concurrently as burning flues and combustion is maintained concurrently in the flues of all of the heating walls of the battery.

30 The cross-wise regenerators 18 of the retort oven or battery are located below the aforesaid heating walls 11 and coking chambers 12, and in the present instance extend in parallelism between the supporting walls 13. 35 Located in the middle lengthwise vertical plane of the coke oven battery, is a vertical partition 19, as shown in Fig. 1, which partition extends all the way up from the mat of the battery to the bottom of the overlying 40 structure and from one to the other of the pillar walls 13. The regenerators, which are respectively located on opposite sides of the battery extend inwardly to said partition 19 and are separated thereby as clearly shown in 45 Fig. 1. This arrangement permits control from opposite sides of the battery of the flow through the regenerators. Each regenerator 18 is a chamber containing open brickwork, commonly called checkerwork, and indicated 50 at 20 with a distributing sole channel 18^a underneath such checkerwork, the channels forming the soles of such chambers and opening up into the checkerwork.

The regenerators are heated, in alternation, 55 by the hot combustion products that draw off from the flame or combustion flues hereinbefore mentioned and then impart such heat to the medium that they feed to these flame flues; in the present instance, the series of 60 regenerators 18 on each side of the central partition 19 are disposed, taken seriatim longitudinally of the battery, in groups G and H, each said group comprising two regenerators and, as shown in Fig. 2, flow is 65 maintained concurrently in the same direc-

tion in all the regenerators of the several groups on one side of the central partition 19, while flow is maintained concurrently in the opposite direction in the several groups of regenerators on the other side of the aforesaid central partition. That is to say, the several groups of regenerators on one side of the partition 19 operate concurrently as inflow regenerators, while the several groups of regenerators on the other side of said partition are operating concurrently as outflow regenerators, this being a common practice, as set forth in the well-known Koppers cross-regenerative Patent No. 818,033 dated April 17, 1906. On reversal of the battery, by means of any preferred type of reversing mechanism, the several groups of regenerators which heretofore operated as outflow regenerators become inflow regenerators and concurrently the several groups of regenerators that heretofore operated as inflow regenerators become outflow regenerators.

Located at the opposite ends of each heating wall are vertical feed channels 21 and 22, the said channels preferably having inner vertical walls 23 and outer walls 24 which incline upwardly toward the aforesaid vertical walls 23, as shown in Fig. 1. There is a pair of such channels 21 and 22 at each end of each heating wall, the channels 21 on one side of the aforesaid partition 19 being respectively connected with the ends of the several flues 17 by means of ports 25, and the channels 22 on the opposite side of the partition 19 being connected with the opposite ends of their corresponding flues by means of ports 26. This arrangement provides ports connecting respectively the opposite ends of each series of flues with pairs of channels corresponding to and positioned at the opposite ends of such flues.

When burning an extraneously derived fuel gas, such as producer gas in the flues 17, each inflow group of regenerators is composed of a gas regenerator P for heating the fuel gas and an air regenerator A for heating the air which enters the flues to support combustion of the gas. All of the outflow groups of regenerators operate concurrently as waste gas regenerators and are designated by the reference character W. As shown in Fig. 2 the gas regenerators P are disposed adjacent to each other and the air regenerators A are likewise disposed, there being pairs of air regenerators which alternate with pairs of gas regenerators. The gas regenerators P of each group, whether operating for inflow or for outflow, are respectively communicably connected by ports 27 with feed channels of the pairs 21 or 22; the air regenerators A, whether operating for inflow or for outflow, are respectively communicably connected, by means of ports 28, with the other feed channels of the pairs 21 or 22. With this construction, the flame flues of each heating wall

are communicably connected on one side of the battery with gas and air regenerators and on the other side of the battery with waste gas regenerators, the latter becoming, on reversal, gas and air regenerators and the former becoming waste gas regenerators.

The reversal in operation of the flame flues 17 involves a reversal in direction of flow of the gases through said flues, and a change of the points of supply from one end of each 10 series of flues to the other, with the result that all of the flues of the entire battery may operate concurrently as burning flues, notwithstanding reversal in flow through the regenerators. The function of such regenerators is 15 as follows:—the regenerators that prior to the reversal operated as inflow regenerators become outflow regenerators, and the outflow operating regenerators become inflow operating regenerators; the supply of gas from 20 one side of the battery to all the flues is turned off; and the supply of gas from the other side of the battery to all the flues is turned on.

Extending from the opposite side walls of 25 the battery and leading into the feed channels 21 and 22 are gas supply ducts 29 and 30. These gas supply ducts 29 and 30 register with the ports 25 and 26 at the opposite ends of the flame flues and are for the purpose of optionally supplying coke oven gas to the several flame flues of each heating wall. The supply of coke oven gas to the respective ducts 29 and 30 is derived from coke oven gas mains of the usual type that are respectively located on the opposite sides of the battery. Suitable means is provided for admitting or cutting off the supply of gas with respect to the channels 29 and 30, it being understood 35 that the gas supply, when the oven is operating with coke oven gas, is turned on currently either to the series of ducts 29, or the series of ducts 30.

For operating the battery alternatively for the use of a special generator gas, such as 45 producer gas as a fuel, the several inflow operating regenerators P may be optionally connected with a producer gas main, so that the producer gas may be directed into such of the regenerators as are operating for inflow and 50 conveyed through these regenerators into the burning flame flues 17. The operation of the retort oven or battery when using a special generator gas, such as ordinary producer gas, as a fuel, is as follows: the supply of coke 55 oven gas to the coke oven gas main, and to all of the coke oven gas channels 29 and 30 is cut off. A supply of producer gas is permitted to flow into the inflow operating gas regenerators P, and passing through said regenerators is preheated before being delivered into the burning flame flues. During the 60 inflow of producer gas through such regenerators P, waste gas from the other end of the flues is flowing out through all of the regenerators W, on the other side of the parti-

tion 19. In the regenerators A inflow of air is maintained and, passing upwardly through said regenerators, is preheated and finally enters the burning flame flues to support the combustion of the producer gas that is delivered thereto by the regenerators P. On reversal of the flow, the inflow gas and air regenerators become outflow regenerators, and concurrently the outflow operating waste gas regenerators become inflow gas and air regenerators.

In operating the battery with coke oven gas, the supply of producer gas to the regenerators P is shut off and air is permitted to flow into such regenerators in place of the producer gas. During coke oven gas operation a supply of coke oven gas is maintained in the channels 29 or 30 which feed that end of the burning flues that are in connection with the air regenerators. The reversing mechanism is operated on each reversal to place all of the inflow operating regenerators in communication with the outer air.

Alternatively, during such coke oven gas operation, some of the regenerators, such as 90 the regenerators P may be employed for conveying to the flues a neutral gaseous diluent, such as return waste gas, to lengthen the flames in the flues, in the manner and for the purpose set forth in my co-pending application Serial No. 376,126, filed April 23, 1920.

In the form of the invention illustrated in Fig. 3, single regenerators 31 located below the respective coking chambers 12 are substituted for the pairs of air and gas regenerators A, A and P, P. These regenerators 31 are located between the supporting walls 32, the latter being positioned below the heating walls 11. Each regenerator 31 is communicably connected with flow channels 21 or 22 of two adjacent heating walls by means of ducts 33, whereby the opposite ends of each heating wall are communicably connected by ducts respectively with two adjacent regenerators of both series of opposite sides of the central partition 19. In operating with producer gas as the fuel the gas regenerators P' alternate with the air regenerators A', and each heating wall is supplied with heat and air from its inflow operating side. When 115 using coke oven gas as the fuel all of the inflow operating regenerators feed air to the several channels with which they are connected. The construction of the heating walls and the reversal in operation of the battery 120 is effected in the same manner as that hereinbefore described.

The invention as hereinabove set forth is embodied in a particular form of construction but may be variously embodied within 125 the scope of the claims hereinafter made.

I claim:

1. In a cooking retort oven, in combination: a plurality of parallel horizontally elongated coking chambers; heating walls con-

tiguous to said coking chambers and respectively constituted of horizontal combustion flues; reversible crosswise extending regenerators parallel with the coking chambers and the heating walls, said regenerators being disposed into two series located on opposite sides of the battery respectively, one series operating for inflow while the other series operates for outflow, the regenerators of each series being grouped in pairs with one inflow operating regenerator of each pair for supplying gas and the other for supplying air; and the pairs of said two series of regenerators having communications with the opposite ends of the horizontal combustion flues, respectively, of said heating walls, each of said communications consisting of a substantially straight duct; substantially as specified.

2. In a coking retort oven, in combination: a plurality of parallel horizontally elongated coking chambers; heating walls contiguous to said coking chambers and respectively constituted of horizontal combustion flues; and reversible crosswise extending regenerators parallel with the coking chambers and the heating walls, said regenerators being communicably connected in pairs by communications with the opposite ends of the combustion flues, respectively, of a single heating wall, each of said communications consisting of a substantially straight duct, the respective regenerators of each pair being operable during the inflow period to convey to said flues air and an extraneously derived gas, such as producer gas; substantially as specified.

3. In a coking retort oven, in combination: a plurality of parallel horizontally elongated coking chambers; heating walls contiguous to said coking chambers and respectively constituted of horizontal combustion flues; and reversible crosswise extending regenerators parallel with the coking chambers and the heating walls, said regenerators being communicably connected in pairs by communications with the opposite ends of the combustion flues, respectively, of a single heating wall, each of said communications consisting of a substantially straight duct; substantially as specified.

50 4. In a coking retort oven, in combination: a plurality of parallel horizontally elongated coking chambers; heating walls contiguous to said coking chambers and respectively constituted of horizontal combustion flues; combined with inflow and outflow crosswise regenerators grouped in pairs along opposite sides of the coking retort oven, the regenerators of the inflow pairs being respectively communicably connected with one end of the combustion flues of a single heating wall and being jointly operable for conveying air to the flues or separately operable for conveying to said flues air or an extraneously derived gas, and the outflow pairs of regenerators being respectively communicably connected

with the opposite end of the combustion flues of a single heating wall; and means for supplying, at will, to said flues an alternative fuel gas, such as coke oven gas; substantially as specified.

5. In a coking retort oven, in combination: a plurality of coking chambers; heating walls contiguous to said coking chambers and respectively constituted of horizontal combustion flues; combined with a plurality of groups of inflow and a plurality of groups of outflow regenerators grouped in pairs which are individual to the respective heating walls and are communicably connected with the opposite ends of the flues, respectively, of the heating walls, the regenerators of the inflow pairs being jointly operable for conveying air to the flues or separately operable for conveying to said flues air or an extraneously derived gas; and means for supplying, at will, to said flues an alternative fuel gas, such as coke oven gas; substantially as specified.

6. In a coking retort oven, in combination: a plurality of parallel horizontally elongated coking chambers; heating walls contiguous to said coking chambers and respectively constituted of horizontal combustion flues; combined with inflow and outflow crosswise regenerators grouped in pairs which are individual to the respective heating walls and are communicably connected with the opposite ends of the flues, respectively, of the heating walls, the regenerators of the inflow pairs being separately operable for conveying to the said flues air and an extraneously derived gas, such as producer gas; substantially as specified.

7. In a coking retort oven, in combination: a plurality of coking chambers; heating walls contiguous to said coking chambers and respectively constituted of horizontal combustion flues; combined with a plurality of groups of inflow and a plurality of groups of outflow regenerators grouped in pairs which are individual to the respective heating walls and are communicably connected with the opposite ends of the flues, respectively, of the heating walls, the regenerators of the inflow pairs being separately operable for conveying to the said flues air and an extraneously derived gas, such as producer gas; substantially as specified.

8. In a coking retort oven, in combination: a plurality of coking chambers; heating walls contiguous to said coking chambers and respectively constituted of horizontal combustion flues; combined with a plurality of groups of inflow and a plurality of groups of outflow regenerators grouped in pairs which are individual to the respective heating walls and are communicably connected with the opposite ends of the flues, respectively, of the heating walls; substantially as specified.

9. In a coking retort oven, in combination: a plurality of coking chambers; heating walls

contiguous to said coking chambers and respectively constituted of horizontal combustion flues; combined with a regenerative system embodying fuel gas and air regenerators communicably connected with one end of the flues of the heating walls, and waste gas regenerators communicably connected with the other end of the flues of said heating walls, the regenerators being individual to the respective heating walls; substantially as specified.

10. A coke oven provided with a series of parallel horizontally elongated coking chambers, heating walls contiguous to said coking chambers and respectively constituted of horizontal combustion flues through which the direction of combustion, in the flues of each of said heating walls, may be in parallel and may be periodically reversed, and crosswise regenerators arranged below and communicating with the opposite ends of the flues, respectively, of said heating walls, substantially as specified.

11. A coke oven provided with a series of parallel horizontally elongated coking chambers, heating walls contiguous to said coking chambers and respectively constituted of horizontal combustion flues through which the direction of combustion may be periodically reversed, fuel gas and air regenerators arranged below and communicating with one end of the flues of said heating walls, and waste gas regenerators arranged below and communicating with the opposite end of the flues of said heating walls, all of the regenerators extending crosswise of the battery; substantially as specified.

12. A coke oven provided with a series of parallel horizontally elongated coking chambers, heating walls contiguous to said coking chambers and respectively constituted of horizontal combustion flues through which the direction of combustion may be periodically reversed, means for supplying heating gases to opposite ends of said combustion flues so that the direction of flow in each flue in each of said heating walls may be maintained simultaneously in the same direction and in parallel with all of the other combustion flues in the same heating wall therewith, and crosswise regenerators arranged below and communicating with the opposite ends of the flues, respectively, of said heating walls, substantially as specified.

13. In a coking retort oven battery, in combination: a series of alternate parallel horizontal coking chambers and heating walls therefor; each of said heating walls comprising a set of superimposed horizontal combustion flues adapted to operate for combustion of gas in parallel simultaneously in the same direction and through which the direction of combustion may be periodically reversed; and crosswise extending regenerators below the coking chambers and heating walls and

arranged in two series of groups operable in alternation with each other for inflow and outflow and with at least a pair of regenerators in each of said groups; each said set of combustion flues being communicably connected at one end thereof with a pair of regenerators of one of the groups of one of said two series thereof and being also communicably connected at the opposite end thereof with a pair of regenerators of one of the groups of the other of said two series thereof.

14. In a coking retort oven battery, in combination: a series of alternate horizontal coking chambers and heating walls therefor, each of said heating walls comprising a set of superimposed horizontal combustion flues adapted to operate for combustion of gas in parallel simultaneously in the same direction and through which the direction of combustion may be periodically reversed; crosswise regenerators below and parallel with the coking chambers and heating walls; said regenerators being disposed in two series located on opposite sides of the battery respectively and being communicably connected in groups with the opposite ends of the combustion flues respectively; and each of said groups of regenerators comprising, when operable for inflow, an air regenerator and a gas regenerator.

15. In a coking retort oven battery, in combination: a series of alternate horizontal coking chambers and heating walls therefor, each of said heating walls comprising a set of superimposed horizontal combustion flues adapted to operate for combustion of gas in parallel simultaneously in the same direction and through which the direction of combustion may be periodically reversed; crosswise regenerators below the coking chambers and heating walls; said regenerators being disposed in two sets operable in alternation with each other for inflow and outflow and that are communicably connected in groups with the opposite ends of the combustion flues respectively; the regenerators of each of said groups, when operable for inflow being jointly operable for conveying air or separately operable for conveying air and gas simultaneously to the flues; and means for conveying, at will, to the opposite ends of said flues an alternative unpreheated fuel gas during joint operation of the regenerators of the respective groups thereof for inflow of air thereto.

16. In a coking retort oven battery, in combination: a series of alternate horizontal coking chambers and heating walls therefor; each of said heating walls comprising a set of superimposed horizontal combustion flues adapted to operate in parallel for combustion of gas in each of the flues of the set simultaneously in the same direction; and crosswise regenerators beneath and parallel with the

coking chambers and heating walls and communicably connected to said flues in groups of at least two regenerators each for simultaneous inflow or outflow, the regenerators of each of said groups of regenerators, when 5 operable for inflow, being jointly operable for conveying air to said flues or separately operable for conveying to said flues air and fuel gas simultaneously; and means for conveying to said flues, at will, an alternative unpreheated fuel gas during joint operation of the regenerators of the respective groups thereof for conveying air to said flues.

17. A coking retort oven battery comprising: a series of alternate horizontal coking chambers and heating walls therefor arranged side-by-side; each of said heating walls comprising a set of substantially parallel superimposed horizontal combustion flues combined with crosswise regenerators beneath and parallel with the coking chambers and heating walls and disposed in two longitudinal series thereof that are located on opposite sides of the battery respectively, 15 and that are respectively communicably connected to said combustion flues in groups that are respectively of at least two regenerators each for simultaneous parallel flow and that are respectively adapted to convey to said 20 flues air and a preheated combustible gas and to remove wastes therefrom in alternation.

18. A coking retort oven battery comprising: a series of alternate horizontal coking chambers and heating walls therefor arranged side-by-side; each of said heating walls comprising a set of substantially parallel superimposed horizontal combustion flues combined with crosswise regenerators beneath and parallel with the coking chambers and heating 25 walls and disposed in two longitudinal series thereof that are located on opposite sides of the battery respectively, and that are respectively communicably connected to said combustion flues in groups of at least two regenerators each that are arranged for simultaneous inflow or outflow and that are adapted 30 to be jointly operable, when operable for inflow, for conveying air to said flues or separately operable for conveying to said flues air and fuel gas simultaneously; and means 35 for conveying to said flues, at will, an alternative unpreheated fuel gas during joint operation of the regenerators of the respective groups thereof for conveying air to said flues.

JOSEPH BECKER.
